UNITED STATES PATENT OFFICE

JOE J. ETTINGER, OF WARSAW, INDIANA

SURGICAL SPLINT

Application filed November 30, 1927. Serial No. 236,623.

The invention relates to surgical splints and it is particularly directed to such splints as are adapted for use in connection with the reduction of a fractured clavicle.

5 The object of the invention is to provide a durable and efficient splint which is adjustable for accommodation to various persons.

The invention is illustrated in the accompanying drawing in which

10 Figure 1 is a plan view of the splint; Fig. 2 a side elevational view of the splint; Fig. 3 an enlarged plan view of the splint having the pads removed; Fig. 4 a side view of the same, and Fig. 5 a front elevational view of 15 the arm pads.

Referring to the illustrative embodiment of the invention the splint frame consists of a transverse plate 1 and a plate 2 secured by the rivets 3 to the plate 2 and depending 20 therefrom. The frame is thus T shaped or having the form of a cross. A series of apertures 4 is formed in the plate 2 through which the cord 5 is laced for securing the pad 6 to the back of the plate 2. Apertures 7 are also formed in the plate 1 through which 25 the cord 8 is laced for securing the pad 8^a to the back of the plate 1. The pads 6 and 8^a may be secured to the plates in any suitable manner since they are intended to protect the 30 wearer from injury or discomfort, and the manner of their attachment to the plates is unimportant.

A tape 9 is secured by the rivet 10 to the lower end of the plate 2 and attached to one 35 end of the tape is a buckle 11 and at the opposite end of the tape is secured a suitable cleat 12.

At each end of the plate 1 are formed two slots 13 and 14 through which the bolts 15 15^a 40 are extended, the heads of the bolts bearing against the back of the plate. Each bolt is provided with a rectangular portion which is engaged in the slot so that the bolt will not turn in the slot but may be moved along the 45 slot to any desired point. A cleat 16 is supported on the bolts 15 and the nuts 17 on said bolts, when tightened, firmly hold the cleat against the front side of the plate 1 in any position with respect to the slots that the cleat 50 may be adjusted. This cleat is prefer-

ably folded at its opposite ends to form a hook shaped member at each end to which the buckles 18 are connected respectively. The cleat is preferably somewhat resilient so that when the nuts 17 are tightened 55 the folded portions 16^a of the cleat will firmly engage the plate 1 and tend to lock the cleat in its adjusted position on the plate.

The cleat 19 at the opposite end of the plate 1 is similar in all respects to the cleat 16 and 60 is supported on the bolts 15^a and tightened against the plate by the nuts 20. The cleat also carries the buckles 21 at its opposite ends.

A pad 22 having a tape 23 secured thereto is adapted to be passed over the shoulder and 65 under the arm of the patient, the ends of the tape 23 being engaged in the buckles 18 and drawn up as much as necessity requires to secure apposition of the fractured parts of the clavicle. The other pad 24 is similarly supported over the other shoulder and under the other arm of the patient and connected to the buckles on the cleat 19 to firmly position the 70 splint on the back of the patient. The tape 9 is passed about the body of the patient and 75 drawn up as tight as may be desired to anchor the lower end of the splint.

In Fig. 1, the pad 22 is shown connected to both buckles 18 and the pad 24 is shown detached from the upper buckle 21 and depending from the lower buckle 21.

By adjusting the cleats laterally in the slots various breadths of shoulders may be accommodated and the pads 22 and 24 applied thereto. Each cleat may be set at an angle with 85 in certain limits when such angularity is desirable to secure proper apposition of the fractured parts. Attached to each pad 22 and 24 is a buckle 25 to which the opposite ends of a tape 26 may be secured. A pad 90 27 is secured to the tape 26 and in use bears against the chest of the patient. This tape 26 holds the front side of the pads in the proper position on the shoulders.

The frame of the splint, formed by the 95 plates 1 and 2, is preferably made of aluminum since that metal is relatively light in weight and is readily maintained in a cleanly condition.

The arm pads 22 and 24 are interchange- 100

able if desired and either may be replaced by a new pad at small cost. The splint, of course, may be used for a fracture of either clavicle.

5 What I claim is:

A surgical splint comprising a flat T-shaped padded frame, two bars laterally adjustably mounted adjacent opposite ends respectively of the cross member of the frame, 10 means to press the bars in adjusted position onto the cross member, each bar being folded at its opposite ends to form buckle-receiving members, said folded portions being adapted to engage the cross member and tending to 15 lock the bars to said member and a pad adjustably engaged by the buckles.

In witness whereof I have hereunto subscribed my name this 19th day of November, 1927.
